Primary Examiner — Cynthia M. Chin(74) *Attorney, Agent, or Firm* — Daryl R. Wright; Greg Carr**(57) CLAIM**

We claim the ornamental design for a transducer mount, as shown and described.

DESCRIPTION

FIG. 1 is a top, left, front perspective view of a transducer mount;

FIG. 2 is a bottom, right, front perspective view thereof;

FIG. 3 is a top plan view thereof;

FIG. 4 is a front elevation view thereof;

FIG. 5 is a bottom plan view thereof;

FIG. 6 is a rear elevation view thereof;

FIG. 7 is a right side elevation view thereof; and,

FIG. 8 is a left side elevation view thereof.

Structural elements depicted by broken lines have been shown for the purpose of illustrating portions of the transducer mount that form no part of the claimed design.
